UNITED STATES PATENT OFFICE.

WILLIAM F. LEE, OF PHILADELPHIA, PENNSYLVANIA.

FRICITION-CLUTCH.

SPECIFICATION forming part of Letters Patent No. 439,960, dated November 4, 1890.

Application filed August 6, 1890. Serial No. 361,188. (No model.)

To all whom it may concern:

Be it known that I, WILLIAM F. LEE, a citizen of the United States, and a resident of Philadelphia, Pennsylvania, have invented 5 certain Improvements in Friction-Clutches, of which the following is a specification.

The object of my invention is to construct an improved friction-clutch for connecting shafts together or for connecting pulleys to 10 shafts. These objects I attain in the following manner, reference being had to the accompanying drawings, in which—

Figure 1 is a longitudinal sectional view of my improved frictional clutch. Fig. 2 is a 15 transverse section on the line 1 2, Fig. 1. Fig. 3 is a view showing a form of clutch I prefer to use to connect a pulley to a shaft. Fig. 4 is a section on the line 3 4, Fig. 2.

Referring in the first instance to Figs. 1 20 and 2, A is the driving-shaft, and A' the driven shaft abutting at the point *a*. On the shaft A is a cone-sleeve B, having the two conical bearing-surfaces *b b*, and in the present instance having the two extensions *b' b'*. This 25 cone-sleeve is secured to the shaft by a key or set-screw, so as to turn with the shaft at all times.

Keyed to the shaft A' is a collar C, and adapted to slide longitudinally on this collar 30 is a clutching-hub D, having one or more pins *d'*, which enter longitudinal slots *c* in the collar C, so as to allow the clutching-hub to have an independent longitudinal movement on the sleeve C, but at the same time locking it 35 to the sleeve as regards any turning movement. The inclined clutching-face *d* is on the same line as the face of the cone-sleeve B, so that when the bearing-surfaces are brought in contact they will be in line with 42 each other.

Pivoted to lugs *e e* by a pivot-pin *f* are levers E E. Formed in the short end of each lever is a socket F, in which is a bearing-block G, of any suitable material—such as 45 brass, wood, or fibrous material—and I prefer to place directly back of this block a thrust-plate *g*. Resting against this plate is a set-screw *h*, which is provided with a jamb-nut *h'*. Thus the bearing-block G can be set up 50 at intervals as it wears away. The face of the bearing-block G is on the same line as the

bearing-face of the cone-sleeve B, so that when forced to bear upon said cone-sleeve the said sleeve will be hugged tightly between the bearing-face *d* of the clutching-hub D and the 55 block G.

Inserted in the face of the clutching-hub D are independent bearing-blocks *i*, which are adapted to undercut cavities in the said bearing-face *d*, as clearly shown in Fig. 2. I 6c prefer to make these bearing-blocks of wood, although other material may be used. The blocks are made in three pieces *i' i² i³*. The end pieces *i² i³* are beveled on one edge to fit the undercut portions of the cavities. 65 When the two blocks *i² i³* are in place, I force the central block *i'* between them and secure it to said blocks by any suitable cement, thus preventing the accidental displacement of the bearing-blocks, as shown in Fig. 4. 70

The long arms of the levers E are in the present instance linked to a sliding sleeve H by links I, pivoted to the sleeve at *j j* and to the long arm of the levers E at *k k*. When the sleeve is in the position shown in Fig. 1, 75 the long arms of the levers are forced outward and the short arms forced against the bearing-surface of the conical sleeve having the double-cone bearing-faces, at the same time drawing up the clutching-hub D tightly 80 against the conical sleeve, locking the two shafts together; but by moving the sleeve H in the direction of the arrow, Fig. 1, the long arms of the levers are drawn toward the center, the short arms thrown outward, and the 85 conical sleeve released from the control of the clutching-hub and clutching-block.

Mounted on an annular rim *d²* on the clutching-hub D is a belt-pulley M, having an internal flange or lugs *m*, which rest against 90 the face of the annular flange *d²*, and are secured thereto by suitable bolts *n*, Fig. 2. The pulley M may be of any diameter necessary, and when a pulley of increased diameter is used the flange *m* may be made up of a series 95 of spokes which are secured to the clutching-hub. In place of the pulley M a protecting-drum may be clamped to the annular flange *d²*, which will protect the parts of the clutch.

When it is wished to merely clutch a driving or driven pulley to a shaft, the collar C is dispensed with, the clutching-hub finding its 100

bearing directly upon the shaft, as shown in Fig. 3, said hub being loose on the shaft.

In order to steady the parts, I prefer to allow one of the extensions b' to enter and 5 snugly fit a cavity in the clutching-hub, as shown in Fig. 1. This extension may be lengthened or shortened, depending altogether on the character of the clutch, and may in some instances be entirely dispensed with.

10 In some instances the clutching-sleeve may be made as shown in Fig. 3, having only one inclined bearing-surface, and the number of levers may be increased, depending upon the power required.

15 I claim as my invention—

1. The combination, in a clutch, of the shaft, a sleeve thereon having one or more inclined clutching-surfaces, a longitudinally-sliding clutching-hub, and clutching-levers 20 mounted on said hub, said hub and levers adapted to close upon the said sleeve, substantially as described.

2. The combination, in a clutch, of the shaft, a conical bearing-sleeve mounted on 25 said shaft and secured thereto, a clutching-hub, an inclined bearing-face adapted to one face of the conical sleeve, levers pivoted to said hub, the short arms of said levers having bearing-faces adapted to bear against the op-

30 posite bearing-surfaces of the conical sleeve, and mechanism for operating said levers, substantially as described.

3. The combination, in a clutch, of the abutting driving and driven shafts, a conical 35 clutching-sleeve secured to one of said shafts, a collar C, secured to the other shaft, a clutch-

ing-hub adapted to slide longitudinally on but turn with the said collar, having a bearing-surface adapted to engage with the bearing-surface on the conical sleeve, levers pivoted to said clutching-hub, having surfaces adapted to engage with the opposite side of said conical sleeve, and mechanism for operating the levers, substantially as set forth. 40

4. The combination of the shaft, a clutching-sleeve mounted on said shaft, a clutching-hub adapted to bear against said sleeve, pivoted arms on said hub, and bearing-blocks adjustably mounted in the short arms of said levers, also adapted to bear against said sleeve, 45 substantially as described.

5. The combination, in a clutch, of the shaft, a clutching-sleeve having oppositely-inclined bearing-surfaces, a clutching-hub adapted to one of said surfaces, levers pivoted to said 50 hub, bearing-blocks on said levers adapted to the sleeve, and screws for adjusting the blocks in the said levers, substantially as described.

6. The combination, in a clutch, of the clutching-hub, the bearing portion thereof 60 having dovetailed cavities with bearing-blocks adapted to said cavities, said blocks being formed of three or more pieces secured together after insertion in the cavities, substantially as described. 65

In testimony whereof I have signed my name to this specification in the presence of two subscribing witnesses.

WILLIAM F. LEE.
